CLASP FOR SPECTACLE CASES

Otto A. Roth, St. Louis, Mo.

Application April 29, 1937, Serial No. 139,800

3 Claims. (Cl. 24—3)

This invention relates to a clasp for spectacle cases and the like, and it consists in the constructions, arrangements and combinations herein described and claimed.

5 Specifically, the invention relates to a clasp which may be readily attached to the case having means cooperative with a wall of the case for frictionally binding upon the material of a garment for retaining the case against accidental loss.

10 It is an object of the invention to provide a clasp which is made from a single strand of wire, bent in such manner as to define a three point clasp, whereby to accommodate thin and thick materials.

15 It is also an object of the invention to provide a clasp which may be readily attached to a case, and which will in nowise interfere with the opening and closing of the lid of the case.

20 Additional objects, advantages and features of invention will be apparent from the following description considered in conjunction with the accompanying drawing wherein

Figure 1 is an elevational view of a spectacle case having my clasp installed.

25 Figure 2 is a side edge view thereof.

Figure 3 is a top edge view,

Figure 4 is a perspective view of the clasp detached.

30 There is illustrated a clasp generally indicated at 10, formed from a single strand of spring wire. As may be clearly seen from Figures 1 and 4, the wire is bent intermediate its length to define an elongated loop portion 11, and at suitable points 35 inwardly of the bight portion 12, the wire is outwardly and downwardly bent to define respective eyelets 13 and finally bent at right angles to form arms 14, the terminations of which are given a slight curvature in a direction toward each other 40 and sharpened to form prongs 15.

It will be noted that the elongated loop 11 is bowed or curved outwardly, as may be seen in Figure 2 for a substantial distance of its length and at a point adjacent the bight portion 12, the

45 loop is given a slight outward or reverse bend, as at 16. It should be noted that respective reaches 13' of the eyelet 13 contact respective legs 11' of the loop 11 at the points of bend 17, and therefore the legs 13' have a curvature similar to the 50 loop 11, thereby forming gripping means as will be more fully explained hereinafter.

In use, the clasp 10 is applied to the rear flat

wall of the case 18, with the prongs 15 engaged in respective vertical edges of the case. In such position, the bight portion 12 will resiliently bear upon the wall of the case, as will the eyelets 13. It will be obvious that upon inserting the case in 5 a pocket of a garment, the edge of a pocket may pass between the case and the bight portion 12 due to the resilience of the wire, and thus be securely retained. In the event that the material forming the pocket is of light weight, a further 10 downward movement of the case within the pocket, will permit the material to pass between the points 17 and come to rest in the eyelets 13. Thus, the case would be retained at three points, namely adjacent the bight 12 and the two 15 points 17.

While a preferred construction has been shown and described, this is by way of illustration only, and I consider as my own, all such modifications as fairly fall within the scope of the appended 20 claims.

I claim:—

1. A spectacle case clasp comprising a single strand of wire bent intermediate its length to define a loop, leg portions of the wire being bent to 25 form respective eyelets, the eyelets having a reach portion contacting the leg members, the reach members being bent at right angles and terminating in inwardly directed spurs whereby to secure the clasp on a case. 30

2. A spectacle case clasp comprising a single strand of wire bent intermediate its length to define an elongated loop, said loop having an arcuate curvature throughout the major portion of its length and reversely curved adjacent the 35 bight portion of the loop, the leg portions of the loop being bent to define respective eyelets, the eyelets having a reach portion contacting respective leg members, the reach portions having a curvature corresponding to the loop, each of said 40 reach portions being bent at right angles defining oppositely extended arms, and each of said arms terminating in an inwardly directed spur member, whereby to secure the clasp upon a case.

3. A spectacle case clasp comprising a single 45 strand of wire bent intermediate its length to define a loop, leg portions of the wire being bent to form respective eyelets, the eyelets having a reach portion contacting the leg members, the reach members being bent at right angles and 50 terminating in means for attachment to the case.

OTTO A. ROTH.
